UNITED STATES PATENT OFFICE.

ALFRED A. HINDS AND LAMBERT E. MACE, OF LEXINGTON, INDIANA.

PORTABLE CHUTE.

SPECIFICATION forming part of Letters Patent No. 312,468, dated February 17, 1885.

Application filed January 2, 1885. (No model.)

To all whom it may concern:

Be it known that we, A. A. HINDS and L. E. MACE, of Lexington, in the county of Scott and State of Indiana, have invented certain new and useful Improvements in Portable Chutes; and we do hereby declare that the following is a full, clear, and exact description thereof, reference being had to the accompanying drawings, and to the letters of reference marked thereon, which form part of this specification.

The invention relates to inclined slideways, and is specially adapted to transfer tiles, bricks, or similar articles from the drying-shed to the kiln, or from the kiln to the yard. The slideway is made in sections, each of which has its floor composed of rollers having bearings in the sides of the sections. A removable cover or housing may be placed over each section to protect the articles passing thereover from the rain. The rear or delivering section of the slideway is curved and reversible end for end, so as to deliver to either side, as desired. A plane inclined in a reverse direction to the slideway is connected to the rear section, so that the bricks or tiles sliding thereon from the rear section may have their momentum gradually lessened and be brought to a stop.

In the drawings forming part of this specification. Figure 1 is a plan view, partly broken away, of my improved chute. Fig. 2 is a central vertical section of the same on line $x-x$, Fig. 1. Fig. 3 is a section on line $y-y$ on Fig. 2. Fig. 4 is a detail side view.

In the accompanying drawings, A represents the slideway composed of any number of similar sections, B B, composed of the side beams or strips, b b, and the rollers b' b', having opposite bearings in the side beams. The longitudinal sections of the rollers may have any desired contour, but are, preferably, rectangular for the transfer of bricks or similar rectangular articles.

C is a removable housing attached to each section by means of the rods C' and staples C'.

The sections are connected at their meeting ends by means of the hooks D on the ends of one section, engaging in the staples d on the ends of the adjacent sections. The sections are supported by the pivoted legs E, and ren-

dered adjustable in inclination by setting the said legs in positions more or less inclined. The delivering section F is made on a curve, and has hooks D at either side and capable of 55 engaging staples d on the end of the adjacent section.

G is an inclined plane continuing the slideway, but with a reverse inclination, so that the articles passing from the rear section B will 60 be brought to a stop thereon, as explained. The meeting end of the inclined plane G is provided with staples d, which engage with the hooks on the end of the curved section F. The inclined plane G is provided with proper 65 side strips to prevent articles from sliding off laterally, and is supported upon pivoted legs g, by means of which its inclination is made adjustable, as shown.

When it is necessary to alter the inclination 70 of parts, the legs E and g are always turned in the direction in which they will brace the slideway.

Having described our invention, we claim—

1. A slideway for tiles, bricks, or other articles composed of sections coupled end to end by proper devices, and with its rear or delivering section curved and reversible end for end to deliver the articles to either side, substantially as specified. 75

2. The combination, with an adjustable inclined slideway, of an adjustable plane inclined in an opposite direction to the slideway and attached to its delivering end, in order to gradually lessen the momentum of the articles 85 passing thereover and bring them to a stop, substantially as specified.

3. The combination, with the adjustable inclined way A, composed of the sections B, having their floors formed of rollers with opposite bearings in their sides, of the removable housing C, formed in sections and attached to the sections of the slideway by the rods C' and staples C', substantially as specified. 90

In testimony that we claim the foregoing as 95 our own we affix our signatures in presence of two witnesses.

ALFRED A. HINDS.
LAMBERT E. MACE.
